(57) **CLAIM**

The ornamental design for a curved flexible male urinary catheter, as shown and described.

DESCRIPTION

FIG. 1 is a perspective view of a curved flexible male urinary catheter;

FIG. 2 is a front side view thereof;

FIG. 3 is a back side view thereof;

FIG. 4 a top side view thereof;

FIG. 5 is a bottom side view thereof;

(Continued)

FIG. 6 is a left side view thereof; and,
 FIG. 7 is a right side view thereof.
 The broken lines in FIG. 1 through FIG. 7 form no part of
 the claimed design.

1 Claim, 7 Drawing Sheets
